UNITED STATES PATENT OFFICE.

WILLIAM S. GRISWOLD, OF GUTHRIE, OKLAHOMA.

TRACK-SANDER.

1,356,982.

Specification of Letters Patent. Patented Oct. 26, 1920.

Application filed April 24, 1920. Serial No. 376,340.

To all whom it may concern:

Be it known that I, WILLIAM S. GRISWOLD, a citizen of the United States, residing at Guthrie, in the county of Logan and State 5 of Oklahoma, have invented certain new and useful Improvements in Track-Sanders, of which the following is a specification, reference being had to the accompanying drawings.

10 This invention relates to track sanding devices for railway locomotives, and particularly to that class of track sanders wherein compressed air is used as a means for discharging sand in a blast upon the track.

15 The general object of this invention is to provide a track sanding device of this character which is very simple and effective in operation, and in which sand is prevented from blowing back into the air line 20 of the rear sanding mechanism while the front sanding mechanism is in use or blowing into the front sanding mechanism when the rear sanding mechanism is in use.

25 A further object is to provide a device of this character which will economize sand and which will operate with a minimum amount of air, and which is entirely watertight.

30 A further object is to provide a sander 35 of this character having a sand holding body, a nozzle extending therefrom, a valve normally closing said nozzle but shiftable to unclose the nozzle, and means whereby when the valve is shifted to permit the sand 40 to pass out through the nozzle a stream of compressed air shall be discharged through the nozzle to cause the forcible ejection of the sand therefrom.

45 A further object is to provide means for operating said valve by compressed air, and provide means whereby, when the compressed air is shut off, the valve will automatically return to its initial position and cut off the flow of sand through the dis-

charge nozzle.

50 A further object is to provide a construction of this character in which the valve and its allied parts may be readily detached from the body for repair or replacement and permit the cleaning out of the body when necessary.

Other objects will appear in the course of the following description.

55 My invention is illustrated in the accompanying drawings, wherein:—

Figure 1 is a side elevation of a locomo-

tive embodying my improved track sanding mechanism;

Fig. 2 is a longitudinal sectional view of the track sanding mechanism; 60

Fig. 3 is a section on the line 3—3 of Fig. 2;

Fig. 4 is a top plan view of one of the valves.

Referring to these drawings, it will be 65 seen that my sanding mechanism comprises a body 10 which is so formed as to provide a medially disposed sand containing chamber and two laterally extending cylindrical portions 11. These portions 11 at their 70 outer ends are formed with screw-threads 12, and the body 10 is provided in its bottom with an opening normally closed by a plug 13, this opening forming a clean-out opening. Passing through the bottom at 75 spaced points therein are the discharge pipes 14 which preferably extend above the bottom of the body 10, as indicated in Fig. 2, and coupled to the discharge pipes are the forward and rear pipe sections 15 which, 80 as illustrated in Fig. 1, extend in divergent relation down concentrically to the locomotive wheels and are supported in any suitable manner.

Engaging in the screw-threaded ends of 85 the front and rear extensions 11 are the cylinders 16, these cylinders having an internal diameter approximately the same as the largest internal diameter of the extension 11 but being reduced, at 17, to engage 90 the screw-threads 12. Then the cylinder is still further reduced, as at 18, for a portion of its length and then again further reduced, as at 19, this portion 19 forming a stuffing box to be filled with felt packing 95 20. Disposed within each cylinder 16 is a piston and a piston rod, this piston rod, which constitutes the valve stem, being designated 21, and passing out through the stuffing box 19 and at its extremity carrying upon it the valve 22 which is preferably pivoted to the piston rod. This valve is in the form of a flat plate having a medially disposed, upwardly inclined rib 23 which extends into a slot formed in the extremity of the corresponding piston rod 105 and is fastened thereto by a screw 24. Each valve plate 22 is adapted to lie upon and close the upper end of the corresponding discharge pipe 14. Each piston rod is 110 formed with a longitudinal bore or passage 25 which opens into the cylinder 16 and

extends longitudinally through the rod and then extends downward to a discharge opening 26 formed on the under side of the piston rod. Thus, when the valve 22 is opened, the discharge opening 26 will be disposed axially above the corresponding discharge pipe 14.

Carried upon the piston rod is a substantially conical piston head 27 upon which is disposed the leather cylinder packing 28, held in place by the conical member 29 and by a follower 30, the piston head being held upon the piston by means of the nut 31. A spring 32 is disposed within the section 18 of the cylinder and bears against a piston head urging the piston outward. The outer end of the section 16 of the cylinder is closed by a cap 33 engaged with the cylinder in any suitable manner and having the compressed air inlet opening 34 formed with a nozzle adapted to engage with an air pipe 35 leading from any suitable source of compressed air. Within the cylinder section 16 is a strainer 39 which will prevent dust or other foreign matter from entering the cylinder with the compressed air. It will be understood that each of the cylinders 16 and the corresponding valve is constructed and operated in the same manner and, as illustrated in Fig. 1, the body 10 is connected to a sand box 40, there being a sand box, as usual, for each locomotive. The inlet of compressed air to the pipes 38 is controlled by a suitable valve or valves in the cab of the engineer.

In the operation of this mechanism, either one of the valves 22 may be operated independently of the other valve, and when it is desired to operate the valve, the compressed air is turned on in the corresponding pipe 38 and this compressed air, entering the cylinder section 16, forces the piston 27 forward from the position shown on the left hand side of Fig. 2 to the position shown on the right hand side thereof, thus carrying the valve 22 off of its seat on the upper end of the corresponding discharge pipe section 14 and carrying the air discharge opening 26 over to the center of the pipe. Under these circumstances, of course, the sand within the member 10 can be discharged through the discharge pipe and this sand will be discharged through said pipe and forced out therefrom by the action of the compressed air discharging into the pipe 14 through the opening 26, this air acting to suck the sand into the discharge opening. When sufficient sand has thus been discharged, the valve in pipe 38 is closed. For a short time the compressed air within the chamber 16 will pass out through the duct 30 and be discharged through the discharge pipe, but when the pressure decreases in the cylinder section 16 beyond a predetermined

point, the spring 32 will act to force the piston head outward, thus causing the valve to close and cutting off the supply of sand.

It will be seen that the body 10 is cast all in one piece and screws into the sand box, thus making it absolutely water-tight, and thus no moisture can get to the sand to thereby cause it to clog. The valve 22 is so constructed that it may easily pass through the body of sand 10 without being so impeded as would prevent the proper operation of the device. If the piston head needs new packing or the spring 32 needs replacement, or the packing needs to be replaced, it is a relatively easy matter to withdraw the cylinder formed of the sections 16, 17, 18 and 19 from the extremity of the branch 11 or the cap 33 may be unscrewed from the cylinder section 16 and the piston withdrawn in this manner. In other words, the piston, piston rod and the valve 22 with the packing may be all withdrawn as a unit from the body 10, thus making it relatively easy to make any repairs necessary, and further making it easy to clean out the sand chamber in the body 10, if by any chance the sand should clog or the chamber 10 should become obstructed.

Of course, it will be understood that the pipes 14 and 15 are clamped to the frame of the locomotive and that the forward pipe 95 is used when the locomotive is going forward and the rear pipe used when the locomotive is going backward. The packing 20 forming the stuffing box for the forward end of the stem 21 is of importance, as if no 100 packing is used to form this stuffing box and, for instance, the front sanding pipe 15 should become clogged or frozen up at the end next to the rail and the front sander should be operated, it would fill up with 105 air and sand and cause a blow back in the body 10, there would be an outlet in the piston rod or stem 21 in the back sander, and then the air would carry dust and small grains of sand back with it into the cylinders and air line. Then when the back sander was used, the dust and sand would clog the operation of the piston rod 21 of the back sander. The sand, of course, will clog in the lateral branches 11 of the body 115 10 and all the space in the body 10 will be filled with sand and, of course, sand will flow from the sand box 40 by gravity and keep the body 10 clear at all times.

The reason for having the discharge pipe 120 14 projecting above the bottom of the casing 11 is that if the slide valves were placed on the bottom of the body or adjacent the bottom of the body, all the gravel that would accumulate from the sand not being properly screened would interfere with the operation of the valve. The valves 22 are, of course, removable from the forward ends

of the piston rods or stems so that the valves can be detached and the piston rods removed from the cylinder.

While I have illustrated a form of my invention which I believe to be particularly valuable, I do not wish to be limited thereto, as it is obvious that many changes might be made therein without departing from the spirit of the invention as defined in the appended claims.

I claim:

1. A track sanding mechanism of the character described including a sand receiving body having a vertical discharge pipe, a valve movable in a horizontal plane from a position obstructing the discharge pipe to a position permitting flow of sand therethrough, a valve rod extending laterally from the valve and having a longitudinally extending duct opening upon the bottom of the piston rod adjacent the valve whereby when the valve is shifted to a position to uncover said upper end of the discharge port the bore of the valve will register with the discharge pipe, manually controllable means for admitting compressed air to said duct and shifting the valve from its closed position to its open position to uncover the upper end of the discharge pipe, and means urging the valve in a position to cover the discharge pipe.

2. A track sanding mechanism of the character described including a sand receiving body having a discharge pipe, a cylinder extending laterally from the body and connected at its outer end to a source of compressed air, means for admitting compressed air to the cylinder, a piston operating therein and having a tubular piston rod, a valve carried upon the outer end of the piston rod and adapted to close over the discharge pipe, said passage through the piston rod opening upon the under side thereof and, when the valve is opened, discharging into the discharge pipe, and a spring urging the piston outward and the valve to a closed position.

3. A track sanding device comprising a sand receiving body having a discharge pipe, said body having a lateral extension, a cylinder disposed in said lateral extension and connected at its outer end to a source of compressed air, a piston head disposed in the cylinder and having a stem extending out of the inner end of the cylinder, a valve carried upon the inner end of the stem and adapted to close the discharge pipe, said stem having a duct extending from the outer end thereof and discharging on the under face of the rod back of the valve, packing disposed within the cylinder through which the piston rod passes, a spring disposed on the cylinder and urging the piston head outward, and manually con-

trollable means for admitting compressed air to the cylinder.

4. A track sanding device including a sand receiving body having a discharge pipe extending therefrom and having a lateral branch screw-threaded at its extremity, a cylinder having screw-threaded, detachable engagement with the outer end of said branch and having packing at its inner end, a piston head operating within the cylinder and passing through said packing, a valve carried upon the extremity of the piston rod and normally preventing the passage of sand through the discharge pipe, said piston rod having a duct extending from its outer end to a point behind the valve and then extending downward to the under side of the piston rod, packing carried by the piston head and bearing against the cylinder, a spring urging said piston outward, and manually controllable means for admitting compressed air to the cylinder.

5. A track sanding device including a sand receiving body having a discharge pipe extending therefrom and having a lateral branch screw-threaded at its extremity, a cylinder having screw-threaded, detachable engagement with the outer end of said branch and having packing at its inner end, a piston head operating within the cylinder and passing through said packing, a valve carried upon the extremity of the piston rod and normally preventing the passage of sand through the discharge pipe, said piston rod having a duct extending from its outer end to a point behind the valve and then extending downward to the under side of the piston rod, packing carried by the piston head and bearing against the cylinder, a spring urging said piston outward, manually controllable means for admitting compressed air to the cylinder, said cylinder having a detachable cap at its outer end, and a strainer disposed within the cylinder inward of this cap.

6. A track sander of the character described including a sand receiving body having two discharge pipes in spaced relation to each other, the body provided with two oppositely extending branches, cylinders operatively and detachably engaged with the extremity of each branch, piston heads carried in said cylinders, piston rods carried by each head and extending through the inner end of the corresponding cylinder, a valve carried on the extremity of each piston rod and adapted to prevent the passage of sand through the corresponding discharge pipe, each piston rod being formed with a longitudinally extending duct opening at one end upon the outer end of the piston rod and at its other end extending downward and discharging upon the under face of the piston rod inward of the valve,

packing carried by the piston head and engaging the cylinder, a spring urging each piston head outward, flexible pipes extending from each discharge pipe and operatively and detachably engaged therewith, and manually controllable means for admitting compressed air to either of said cylinders behind the piston thereof.

7. In a locomotive, driving wheels, a sand container, a sand receiving body below and engaged with the sand container and having two discharge pipes, sand pipes extending from said discharge pipes to points forward and rearward of the driving wheels, valves controlling the discharge through each pipe and disposed within the body, resilient means normally urging said valves to a closed position, manually controllable com-

pressed air operated means for shifting either of said valves independently of the other valve to an open position, and means for discharging compressed air into the discharge pipes when the valves are open.

8. A track sanding device comprising a sand receiving body having a discharge pipe extending upward through the bottom of the body and having its opening disposed above the bottom of the body, a valve normally seated upon the upper end of the discharge pipe and yieldingly held in this position, and air operated means for forcing said valve from its seat to permit the discharge of sand through the discharge pipe.

In testimony whereof I hereunto affix my signature.

WILLIAM S. GRISWOLD.
